(57) **ABSTRACT**

The present disclosure relates to the field of display technology, and provides a display device and a driving method therefor. The driving method includes: providing a display device including a plurality of sub-pixels, each sub-pixel including an OLED light-emitting element, a light-emitting control transistor configured to transmit a driving current to the OLED light-emitting element, and a reset transistor coupled to an anode of the OLED light-emitting element; inputting a periodic cut-off signal to the light-emitting control transistor; determining the effective light-emitting phase of each frame period for the sub-pixel; and during the effective light-emitting phase of each frame period for the sub-pixel, inputting a reset signal to the reset transistor corresponding to one or more cut-off signal.

DISPLAY DEVICE AND DRIVING METHOD
THEREFOR

The present application is a 35 U.S.C. 371 national phase application of PCT International Application No. PCT/CN2021/100968 filed on Jun. 18, 2021, which PCT International Application claims the priority of Chinese patent application No. 202010889868.7 filed on Aug. 28, 2020, the entries disclosures of both are incorporated herein by reference.

TECHNICAL FIELD

The present disclosure relates to the field of display technology, in particular to a display device and a driving method therefor.

BACKGROUND

Organic Light-Emitting Diode (OLED) display devices are prone to flicker problems under display conditions with low frame rates. The flicker problem is caused by leakage current or hysteresis voltage. There have been many studies on improving leakage current in the relevant art. The present disclosure mainly focuses on hysteresis voltage.

The driving current I_{OLED} of the OLED light-emitting element is generated according to the following formula (1):

$$I_{OLED} = K(V_{DATA} - ELVDD)^2 \quad (1)$$

where K is the contact value, V_{DATA} is the data voltage, and $ELVDD$ is the power supply voltage. The brightness error ΔI_{OLED} of the OLED light-emitting element is generated according to the following formula (2):

$$\sqrt{\frac{\Delta I_{OLED}}{I_{OLED}}} = 1 + \frac{\Delta V_{th}}{V_{DATA} - ELVDD} \quad (2)$$

where ΔV_{th} is the hysteresis voltage. According to the formula (1) and the formula (2), it may be known that the value of $(V_{DATA} - ELVDD)$ becomes smaller at low gray levels, and thus the luminance error will increase under the same value of the hysteresis voltage ΔV_{th} . Therefore, the flicker problem becomes more serious under display conditions with low frame rate and low grayscale.

The principle of flicker caused by the hysteresis voltage is that during the initial phase of each frame period, the OLED light-emitting element has a light-emitting delay phenomenon due to the existence of hysteresis voltage, which causes a period of brightness delay of the display brightness in the initial phase of each frame period. Under display conditions with low frame rate and/or low grayscale, this period of brightness delay is perceived by human eyes, resulting in visual flicker.

Especially in display devices using Variable Refresh Rate (VRR) technology, since the sensitivity of human eyes to flicker increases with the decrease of flicker frequency, VRR technology helps to reduce the frame rate to 25 Hz at least, resulting in extremely severe visual flicker.

It should be noted that the information disclosed in the above background section is only used to enhance understanding of the background of the present disclosure, and therefore may include information that does not constitute prior art known to those of ordinary skill in the art.

SUMMARY

In view of above, the present disclosure provides a display device and a driving method therefor to solve the problem of visual flicker.

2

An aspect of the present disclosure provides a driving method for a display device, comprising steps of: providing a display device, the display device comprising a plurality of sub-pixels, each sub-pixel comprising an OLED light-emitting element, light-emitting control transistor for transmitting a driving current to the OLED light-emitting element, and a reset transistor coupled to the anode of the OLED light-emitting element; inputting a periodic cut-off signal to the light-emitting control transistor; determining an effective light-emitting phase of each frame period for the sub-pixel; and, in the effective light-emitting phase of each frame period for the sub-pixel, inputting a reset signal to the reset transistor corresponding to one or more cut-off signal.

In some embodiments, the step of determining the effective light-emitting phase of each frame period for the sub-pixel includes: inputting an initial reset signal whose period is the frame period to the reset transistor; acquiring the delay light-emitting time of the sub-pixel in response to the initial reset signal; and configuring a phase after the delay light-emitting time in each frame period as the effective light-emitting phase.

In some embodiments, in the step of inputting the reset signal to the reset transistor, determining the input frequency of the reset signal according to the frame period and the delay light-emitting time, so that within each frame period, the brightness delay caused by the delay light-emitting time and the reset signal is invisible in frequency.

In some embodiments, the reset signal is a periodic or aperiodic pulse signal.

In some embodiments, a parasitic capacitance exists between the anode and the cathode of the OLED light-emitting element. In response to the initial reset signal, the driving current charges the parasitic capacitance of the OLED light-emitting element before flowing through the OLED light-emitting element, so that the OLED light-emitting element generates the delay light-emitting time.

In some embodiments, each sub-pixel further includes a driving transistor for generating the driving current, and the driving transistor is connected to the OLED light-emitting element through the light-emitting control transistor.

Another aspect of the present disclosure provides a display device, including a plurality of sub-pixels arranged in a matrix of rows and columns. Each sub-pixel includes: an OLED light-emitting element; a light-emitting control transistor configured to transmit a driving current to the OLED light-emitting element; and a reset transistor, coupled to the anode of the OLED light-emitting element. The light-emitting control transistor receives a periodic cut-off signal. Each frame period of the OLED light-emitting element has an effective light-emitting phase. The reset transistor is configured to receive a reset signal corresponding to one or more cut-off signal in the effective light-emitting phase of each frame period.

In some embodiments, the reset transistor is further configured to receive an initial reset signal whose period is the frame period, the OLED light-emitting element generates a delay light-emitting time in response to the initial reset signal, and the effective light-emitting phase is a phase after the delay light-emitting time in each frame period.

In some embodiments, the input frequency of the reset signal is related to the frame period and the delay light-emitting time, so that within each frame period, the brightness delay resulting from the delay light-emitting time and the reset signal is invisible in frequency.

In some embodiments, each sub-pixel further includes a driving transistor, configured to generate the driving current,

and the driving transistor is connected to the OLED light-emitting element through the light-emitting control transistor.

The beneficial effects of the present disclosure at least include the following aspects.

In the effective light-emitting phase of each frame period, the reset transistor is used to reset the OLED light-emitting element corresponding to the black picture generated by the cut-off signal, so that there will be a short brightness delay when the OLED light-emitting element emits light after the black picture. The short brightness delay is further used to supplement the flicker frequency caused by the inherent brightness delay of the OLED light-emitting element in the initial phase of each frame period. This helps to reduce the observability of the overall flicker frequency caused by the brightness delay, thereby eliminating visual flicker.

It is to be understood that both the foregoing general description and the following detailed description are exemplary and explanatory only and are not restrictive of the present disclosure.

BRIEF DESCRIPTION OF THE DRAWINGS

The accompanying drawings, which are incorporated in and constitute a part of this specification, illustrate embodiments consistent with the present disclosure and together with the description serve to explain the principle of the present disclosure. Apparently, the drawings in the following description are only some embodiments of the present disclosure, and those skilled in the art can obtain other drawings according to these drawings without creative efforts.

FIG. 1 shows a schematic circuit diagram of a sub-pixel of a display device in an embodiment of the present invention;

FIG. 2 shows a schematic diagram of steps of a driving method for a display device in an embodiment of the present invention;

FIG. 3 shows a schematic diagram of the scene of a driving method for a display device in an embodiment of the present invention;

FIG. 4 shows a schematic diagram of the timing sequence where the delay light-emitting time is caused in an embodiment of the present invention;

FIG. 5 shows the brightness change curve and the flicker visibility curve of a display device where a traditional driving method is adopted; and

FIG. 6 shows the brightness change curve and the flicker visibility curve of a display device where the driving method of the present disclosure is adopted.

DETAILED DESCRIPTION OF THE EMBODIMENTS

Example embodiments will now be described more fully with reference to the accompanying drawings. Example embodiments may, however, be embodied in many forms and should not be construed as limited to the embodiments set forth herein. Rather, these embodiments are provided so that the present disclosure will be thorough and complete, and will fully convey the concept of the example embodiments to those skilled in the art. The same reference numerals denote the same or similar structures in the drawings, and thus their repeated descriptions will be omitted.

Furthermore, the drawings are merely schematic illustrations of the present disclosure and are not necessarily drawn to scale. The same reference numerals in the drawings

denote the same or similar parts, and thus repeated descriptions thereof will be omitted. Some of the block diagrams shown in the drawings are functional entities and do not necessarily correspond to physically or logically separate entities. These functional entities may be implemented in software, or in one or more hardware modules or integrated circuits, or in different network and/or processor means and/or microcontroller means.

The step numbers in the following method embodiments are only used to indicate different execution contents, and do not limit the logical relationship and the execution order among the steps.

FIG. 1 shows the circuit structure of the sub-pixel of the display device in an embodiment, FIG. 2 shows the main steps of the driving method for the display device in an embodiment, and FIG. 3 shows the implementation scene of the driving method for the display device in an embodiment. Referring to FIG. 2, the driving method for the display device in an embodiment mainly includes the following steps. In step S210, a display device is provided. The display device includes a plurality of sub-pixels, and the circuit structure of each sub-pixel is shown in FIG. 1, including the OLED light-emitting element 11, the light-emitting control transistor 12 that transmits the driving current I_{OLED} to the OLED light-emitting element 11, and the reset transistor 13 coupled to the anode of the OLED light-emitting element 11. In step S220, a periodic cut-off signal is input to the light-emitting control transistor. In step S230, the effective light-emitting phase of each frame period for the sub-pixel is determined. In step S240, in the effective light-emitting phase of each frame period for the sub-pixel, the reset signal is input to the reset transistor corresponding to one or more cut-off signal.

Referring to FIG. 3, the signal EM is a periodic turn-off signal input to the gate of the light-emitting control transistor 12. In an embodiment, the signal EM is a periodic high-level signal, which is used to generate a black picture at a certain frequency in each frame period. Specifically, as shown in FIG. 1 and FIG. 3, when the gate of the light-emitting control transistor 12 receives a high-level signal, the light-emitting control transistor 12 is turned off, and the driving current I_{OLED} cannot be transmitted to the OLED light-emitting element 11 through the light-emitting control transistor 12, thereby causing the brightness of the OLED light-emitting element 11 corresponding to the high level phase of the light-emitting control transistor 12 to be reduced to zero, and generating a black picture. In an embodiment, the signal EM includes 32 high level signals within a frame period (Frame), and the signal EM may be provided to the gate of the light-emitting control transistor 12 in the form of a periodic pulse signal. In an embodiment, the frame period (Frame) is, for example, 30 Hz.

In an embodiment, in the effective light-emitting phase of each frame period, corresponding to the black picture generated by the cut-off signal, the reset transistor is used to reset the OLED light-emitting element, so that a short brightness delay occurs when the OLED light-emitting element emits light after the black picture passes. The short brightness delay is used to supplement the inherent brightness delay of the OLED light-emitting element in the initial phase of each frame period, so that the overall observability of the flicker frequency caused by the brightness delay is reduced, thereby eliminating visual flicker.

In one embodiment, the step of determining the effective light-emitting phase of each frame period for the sub-pixel includes: inputting an initial reset signal whose period is the frame period to the reset transistor; acquiring a delay light-

emitting time of the sub-pixel in response to the initial reset signal; and configuring the phase after the delay light-emitting time in each frame period as the effective light-emitting phase.

As shown in FIG. 1 and FIG. 3, the signal S_n is a level signal received by the gate of the reset transistor **13**, and the signal S_n includes the initial reset signal **301** whose period is the frame period. There is a parasitic capacitance C_{OLED} between the anode and the cathode of the OLED light-emitting element **11**. In response to the initial reset signal **301**, the driving current I_{OLED} charges the parasitic capacitance C_{OLED} of the OLED light-emitting element **11** firstly before flowing through the OLED light-emitting element **11**, thereby causing the OLED light-emitting element **11** to generate the delay light-emitting time t_{DELAY} .

Specifically referring to the principle shown in FIG. 4, in the initial phase of a frame period, when the initial reset signal **301** is input to the gate of the reset transistor **13**, the EM signal is at a high level, and the OLED light-emitting element **11** does not work. The reset transistor **13** is configured to discharge the parasitic capacitance C_{OLED} of the OLED light-emitting element **11**, so as to prevent the contrast from decreasing. When the initial reset signal **301** is set to a high level, the EM signal is set to a low level, the reset process ends, and the OLED light-emitting element **11** enters a light-emitting phase. However, due to the existence of the parasitic capacitance C_{OLED} , the driving current I_{OLED} , that should have flowed through the OLED light-emitting element **11** during the light-emitting phase (that is, flowing from the anode of the OLED light-emitting element **11** to the cathode thereof and caused the OLED light-emitting element **11** to emit light), firstly charges the parasitic capacitance C_{OLED} and then flows through the OLED light-emitting element **11**. Thus, the OLED light-emitting element **11** enters the effective light-emitting phase. Therefore, in the initial phase of the frame period, due to the charging process of the parasitic capacitor C_{OLED} , there is a certain time delay for light emission of the OLED light-emitting element **11**. This is shown in FIG. 4, where the anode voltage V_{ANODE} of the OLED light-emitting element **11** gradually rises to a predetermined value in the initial phase of the frame period, and the brightness Luminance of the OLED light-emitting element **11** has a delay light-emitting time t_{DELAY} in the initial phase of the frame period.

The delay light-emitting time t_{DELAY} is specifically determined according to the following formula (3):

$$t_{DELAY} = \frac{C_{OLED}V_F}{I_{OLED}} \quad (3)$$

wherein V_F is the forward voltage drop of the OLED light-emitting element **11**, that is, the voltage value between the anode and the cathode of the OLED light-emitting element **11** for ensuring the normal light emission of the OLED light-emitting element **11**.

The delay light-emitting time t_{DELAY} is gray-scale dependent. Under display conditions with high grayscale (high driving current I_{OLED}), the delay light-emitting time t_{DELAY} is a very small value and may be ignored.

In FIG. 3, the influence caused by the delay light-emitting time t_{DELAY} is manifested in that a light-emitting delay **303** exists in the light-emitting brightness of the sub-pixel during the initial phase of a frame period (Frame). Under display conditions with low grayscale and low frame rate, the inherent brightness delay **303** caused by the hysteresis

voltage of the sub-pixel will cause visual flicker. Therefore, in an embodiment, in each frame period, a certain short brightness delay **304** is inserted after the inherent brightness delay **303**, so as to increase the occurrence frequency of the brightness delay in each frame period. Thereby, the human eye's sensitivity to flicker caused by the brightness delay is decreased, thus achieving the effect of visual flicker elimination.

The way of inserting a short brightness delay, as described in step **S240** above, is to input a reset signal corresponding to one or more cut-off signal to the reset transistor during the effective light-emitting phase of each frame period of the sub-pixel. For example, as shown in FIG. 3, in the effective light-emitting phase **300** of a frame period (Frame) of the sub-pixel, five reset signals **302** are input to the reset transistor through the signal S_n . The five reset signals **302** correspond to five phase-spaced cut-off signals. The reset signal **302** may be a periodic or non-periodic pulse signal, and its specific input frequency is determined according to the frame period and the delay light-emitting time, so that in each frame period, the brightness delay generated by the delay light-emitting time and the reset signal is invisible in frequency. The reset signal **302** is the same in function as the initial reset signal **301**, and both are signals capable of realizing the reset operation of the OLED light-emitting element **11**.

As shown in FIG. 1, FIG. 3, and FIG. 4, when the gate of the reset transistor **13** receives the reset signal **302**, the reset transistor **13** will discharge the parasitic capacitance C_{OLED} of the OLED light-emitting element **11**; and when the reset signal **302** ends, the signal S_n is set high, and the signal EM is set low, the driving current I_{OLED} charges the parasitic capacitor C_{OLED} firstly, and then flows through the OLED light-emitting element **11** to emit light. Therefore, after each reset signal **302** of the OLED light-emitting element **11**, there will be a short brightness delay **304** in its light-emitting brightness. The short brightness delay **304** increases the total occurrence frequency of the brightness delay in each frame period, thereby reducing the visual flicker sensitivity caused by the inherent brightness delay **303**, and rendering the overall flicker variation within each frame period to be visually invisible.

Under display conditions with high grayscale, there is almost no inherent brightness delay of the sub-pixel. That is, the delay light-emitting time in the initial phase of each frame period is very small. Thus, the input frequency of the reset signal determined according to the frame period and the delay light-emitting time is very small. This means that the above-mentioned driving method will not affect the display conditions with high grayscale. Similarly, under display conditions with high frame rate, the input frequency of the reset signal determined according to the frame period and the delay light-emitting time is very small. This means that the above-mentioned driving method will not affect the display conditions with high frame rate.

In the above driving method, some conventional method principles and circuit structures are not described, which should not be regarded as a limitation to the present disclosure. For example, as shown in FIG. 1, each sub-pixel circuit **60** is connected to power supply voltage $ELVDD$ and $ELVSS$, and each sub-pixel circuit also includes a driving transistor **14** for generating a driving current I_{OLED} . The driving transistor **14** is connected to the OLED light-emitting element **11** through the light-emitting control transistor **12**.

FIG. 5 shows the brightness change curve and the flicker visibility curve of a display device using a traditional driving method, and FIG. 6 shows the brightness change curve and

the flicker visibility curve of a display device where the driving method of the present disclosure is adopted. Referring to FIG. 5, the frame frequency of the display device is 30 Hz, and the grayscale thereof is 46, for example. In the initial phase of a frame period, the display device has an inherent brightness delay, which is shown as a sudden drop 501 in the brightness change curve 5a. But in the subsequent phase of the frame period, the trend of the brightness change curve 5a is relatively stable. Under display conditions with low frame rate and low grayscale, the sudden drop 501 in brightness at the initial phase of each frame period will cause a strong visual experience, which is manifested as a sharp rise 502 in the flicker visibility curve 5b, resulting in a poor visual flicker for perception.

Referring to FIG. 6, also under the display condition with a frame frequency of 30 Hz and a grayscale of 46, when the driving method of the above-mentioned embodiment is adopted, a short brightness delay is inserted in the effective light-emitting phase of each frame period through the additional reset signal, which is shown as a brightness drop 601 in the brightness change curve 6a. This causes the occurrence frequency of the brightness drop (including one brightness drop 501 and multiple brightness drops 601) in each frame period to be increased, thereby relieving visual feeling. That is, in the flicker visibility curve 6b, the flicker visibility corresponding to the frame rate of 30 Hz is greatly reduced, thereby achieving the effect of visual flicker elimination under display conditions with low frame frequency and low grayscale. Therefore, when the display device is equipped with VRR technology and G-SYNC technology, for example, in some game applications, the situation of visual flicker is greatly improved. At display frame rates of 60 Hz and higher, flicker visibility will not be observed by human eyes.

To sum up, through the above-mentioned driving method, in the effective light-emitting phase of each frame period of the sub-pixel, corresponding to the black picture generated by the cut-off signal, the reset transistor is used to reset the OLED light-emitting element, so that a short brightness delay is generated when the OLED light-emitting element emits light after the black picture passes. The short brightness delay is used to supplement the flicker frequency caused by the inherent brightness delay of the OLED light-emitting element in the initial phase of each frame period, thereby reducing the overall observability of the flicker frequency caused by the brightness delay, and achieving the effect of visual flicker elimination.

An embodiment of the present invention also provides a display device, which includes a plurality of sub-pixels arranged in a matrix of rows and columns. Referring to FIG. 1, each sub-pixel includes: an OLED light-emitting element 11; a light-emitting control transistor 12, configured to transmit the driving current I_{OLED} to the OLED light-emitting element 11; and a reset transistor 13, coupled to the anode of OLED light-emitting element 11. The gate of the light-emitting control transistor 12 receives a periodic cut-off signal, generates a continuous black picture. The OLED light-emitting element 11 has an effective light-emitting phase in each frame period. The reset transistor 13 receives a reset signal corresponding to one or more cut-off signal during the effective light-emitting phase of each frame period, so that a short brightness delay occurs when the OLED light-emitting element 11 emits light after the black picture passes. The short brightness delay is used to supplement the flicker frequency caused by the inherent brightness delay of the OLED light-emitting element 11 in the initial phase of each frame period, so that the overall observability

of the flicker frequency caused by the brightness delay is reduced, thereby achieving the effect of visual flicker elimination.

Each sub-pixel also includes a driving transistor 14 for generating a driving current I_{OLED} , and the driving transistor 14 is connected to the OLED light-emitting element 11 through the light-emitting control transistor 12.

Further, the reset transistor also receives an initial reset signal whose period is the frame period, the OLED light-emitting element generates a delay light-emitting time in response to the initial reset signal, and the effective light-emitting phase is a phase after the delay light-emitting time in each frame period. The input frequency of the reset signal is specifically related to the frame period and the delay light-emitting time, so that the brightness delay generated by the delay light-emitting time and the reset signal in each frame period is invisible in frequency.

The display device in this embodiment is driven by the driving method of the above embodiment, so as to achieve the effect of visual flicker elimination. For specific principles, reference may be made to the descriptions of the foregoing embodiments, which will not be repeated here.

To sum up, according to the display device and the driving method therefor of the present disclosure, in the effective light-emitting phase of each frame period of the sub-pixel, corresponding to the black picture generated by the cut-off signal, the reset transistor is used to reset the OLED light-emitting element, so that a short brightness delay occurs when the OLED light-emitting element emits light after the black picture passes. The short brightness delay is used to supplement the flicker frequency caused by the inherent brightness delay of the OLED light-emitting element in the initial phase of each frame period, so that the overall observability of the flicker frequency caused by the brightness delay is reduced, thereby achieving the effect of visual flicker elimination.

The above content is a further detailed description of the present disclosure in conjunction with specific preferred embodiments, and it cannot be assumed that the specific implementation of the present disclosure is limited to these descriptions. For those of ordinary skill in the technical field of the present disclosure, without departing from the concept of the present disclosure, some simple deduction or replacement can be made, which should be regarded as belonging to the protection scope of the present disclosure.

The invention claimed is:

1. A driving method for a display device, comprising steps of:

providing a display device comprising a plurality of sub-pixels, wherein each sub-pixel comprises an OLED light-emitting element, a light-emitting control transistor configured to transmit a driving current to the OLED light-emitting element, and a reset transistor coupled to an anode of the OLED light-emitting element;

inputting a plurality of periodic cut-off signals to the light-emitting control transistor;

determining an effective light-emitting phase of each frame period for the sub-pixel; and

during the effective light-emitting phase of each frame period for the sub-pixel, inputting a reset signal to the reset transistor at the same timing as one or more of the plurality of cut-off signals.

2. The driving method according to claim 1, wherein the step of determining the effective light-emitting phase of each frame period for the sub-pixel comprises:

inputting an initial reset signal to the reset transistor, wherein a period of the initial reset signal is the frame period;

acquiring a delay light-emitting time of the sub-pixel in response to the initial reset signal; and

configuring a phase after the delay light-emitting time in each frame period as the effective light-emitting phase.

3. The driving method according to claim 2, wherein during the step of inputting the reset signal to the reset transistor, an input frequency of the reset signal is determined according to the frame period and the delay light-emitting time, so that in each frame period, a brightness delay resulting from the delay light-emitting time and the reset signal is invisible in frequency.

4. The driving method according to claim 3, wherein the reset signal is a periodic or non-periodic pulse signal.

5. The driving method according to claim 2, wherein a parasitic capacitance exists between the anode and a cathode of the OLED light-emitting element, and in response to the initial reset signal, the driving current charges the parasitic capacitance of the OLED light-emitting element before flowing through the OLED light-emitting element, so that the OLED light-emitting element generates the delay light-emitting time.

6. The driving method according to claim 1, wherein each sub-pixel further comprises a driving transistor for generating the driving current, and the driving transistor is connected to the OLED light-emitting element through the light-emitting control transistor.

7. A display device, comprising a plurality of sub-pixels arranged in a matrix of rows and columns, wherein each sub-pixel comprises:

an OLED light-emitting element;

a light-emitting control transistor, configured to transmit a driving current to the OLED light-emitting element; and

a reset transistor, coupled to an anode of the OLED light-emitting element,

wherein the light-emitting control transistor is configured to receive a plurality of periodic cut-off signals, each frame period of the OLED light-emitting element has an effective light-emitting phase, and the reset transistor is configured to receive a reset signal at the same timing as one or more of the plurality of cut-off signals during the effective light-emitting phase of each frame period.

8. The display device according to claim 7, wherein the reset transistor is further configured to receive an initial reset signal, wherein a period of the initial reset signal is the frame period, and

the OLED light-emitting element is configured to generate a delay light-emitting time in response to the initial reset signal, wherein the effective light-emitting phase is a phase after the delay light-emitting time in each frame period.

9. The display device according to claim 8, wherein an input frequency of the reset signal is related to the frame period and the delay light-emitting time, so that during each frame period, a brightness delay resulting from the delay light-emitting time and the reset signal is invisible in frequency.

10. The display device according to claim 7, wherein each sub-pixel further comprises:

a driving transistor, configured to generate the driving current, wherein the driving transistor is connected to the OLED light-emitting element through the light-emitting control transistor.
